GARMENT CLOSURE CONSTRUCTION

Prima L. Izzo, Waterbury, Conn., assignor to Scovill Manufacturing Company, Waterbury, Conn., a corporation of Connecticut

Filed May 28, 1962, Ser. No. 198,159

5 Claims. (Cl. 2—96)

This invention relates to garments and particularly where snap fasteners are used for closing garment fronts.

Various types of garments, such as cardigans, waist coats, jackets and the like are normally left open but may be closed at the will of the wearer. Such garments have resorted to old conventional button and button hole fastening means. This type of fastening means has been objectionable from an appearance point of view because it is impossible to get a balanced and similar decorative effect on the opposite side of the garment opening. The use of snap fasteners has also been objectionable because at least one of the parts of the snap fastener unit had to be exposed to view if the garment was left in an open position.

It is one of the objects of my invention to construct an open front garment that can make use of snap fasteners and in which the metal or objectionable part of the fastener may be concealed when the garment is open as effectively as when closed.

Another object of this invention is to provide a garment of the above character wherein both sides of the garment will be of like appearance when the garment is left open.

Other objects and advantages of the invention will appear from the following description taken in conjunction with the accompanying drawing wherein:

FIG. 1 is an exemplary use of one type of garment embodying my invention, here shown as a child's jacket;

FIG. 2 is a front view of the garment in open position;

FIG. 3 is a similar view showing the garment in closed position with the lower right hand flap turned up; and

FIG. 4 is a cross-sectional view of the garment on an enlarged scale such as might be taken along the line A—A of FIG. 3 just before the garment is closed.

Referring to the drawing, there is illustrated a child's jacket 10 which comprises a right side 11 and a left side 12 with a front opening 13. The right side 11 has a facing 14 suitably stitched to the underside of the garment adjacent its edge and similarly, the left side 12 of said garment likewise has a facing 15 stitched to the underside thereof.

The means for fastening together the opening portion of the garment makes use of any conventional form of snap fasteners. As a means for reinforcing the garment, and also to add a decorative feature to the garment, there is a series of tabs 16, which may be of contrasting color to that of the garment, secured to the seamed edge of the right front 11 by the same stitching 17 that secures the seamed edges together. The tabs 16 are then folded over upon the right garment front and held there in place either by stitching or by one of the elements of the fastener member which is here shown as an attaching prong ring 18 passing through the garment plies and clinched to a socket member 19.

If it is desired not to have any portion of the fasteners showing on the front of the garment, it is possible to attach the prong rings to only the garment front 11 and the underlying facing 14 and then have the tabs 16 overlie said prong rings and stitched in place.

Considering now the fastener means for the left front 12 of the garment, which will be complementary to the socket 19, said fastener means consists of a series of studs 20 and post members 21 secured together through

2

the garment front material and underlying facing 15 in proper alignment with the right front socket 19.

A series of tabs 22 are attached to the edge of the left front 12 of the garment by the same stitching 23 that secures the left front hemmed edges together. To the outer free end of each of the tabs 22 is secured a fastener element complementary to the stud 20 which in this case, is a prong ring 24 and socket 25 of like construction to the socket 19 on the right front 11.

10 If the garment is to be worn in an open position, such as shown in FIG. 2 and not have the stud 20 exposed, it is only necessary to fold the tabs 22 over upon the left front and snap the sockets 25 upon the studs 20. As shown, both sides of the garment will have a like decorative appearance. Now, if it is desired to hold the garment in a closed position as shown in FIG. 3, it is only necessary to unfasten the sockets 25 and straighten out the tabs 22 to the position shown in FIG. 4, and then move the right front 11 of the garment to overlap the left front 12 and snap the sockets 19 upon the studs 20.

While I have herein described and upon the drawing shown an illustrative embodiment of the invention, it is to be understood that the invention is not limited thereto but may comprehend other constructions and arrangements without departing from the spirit of the invention and the scope of what is claimed, as for instance, instead of having a series of flexible tabs along one edge of the garment, a single flap could be employed having elements attached thereto complementary to the elements on the garment.

What I claim is:

1. In a garment or the like having an opening, complementary male and female snap fastener elements attached to the garment on opposite sides of the opening, said elements having fastening portions facing inwardly along one side whereby they are normally concealed and facing outwardly on the opposite side whereby they are normally exposed when the fasteners are disengaged; the improvement which consists of tabs attached to the garment in line with those fastener elements which are normally exposed, each tab having a fastener element complementary to those on the side to which the tabs are attached so that the tabs may be folded back and snapped over said normally exposed fastener elements in order to conceal them when the garment is open.

2. A garment construction having front portions divided by an opening extending the full length of said garment, a snap fastener element attached to one of the front portions of said garment adjacent the edge defining the opening, a complementary fastener element attached to the opposite front portion of said garment adjacent its edge, a tab attached to one of the edges of said garment in line with one of the fastener elements, and another fastener element secured to said tab extension, said latter element being complementary to the fastener element on that portion of the garment to which the tab is attached whereby said tab may be folded over upon its adjacent garment portion and releasably held in place by said complementary snap fasteners to conceal the fastener elements which are normally exposed on that portion of the garment to which the tab is attached when the garment is in open position.

3. A garment construction having first and second front portions divided by an opening extending the full length of said garment, a tab extension attached to an edge of said first front portion and permanently overlapping said first front portion, a snap fastener element attached to said first front portion and passing through said overlapped tab extension to secure the latter to the face of said front portion, a complementary fastener element attached to the second front portion adjacent its edge, a

second tab extension attached to the second front portion in transverse alignment with said first tab and adapted to normally lie in a common plane with said second front portion, and another fastener secured to said second tab extension, said latter element being complementary to the fastener element on said second portion whereby said second tab extension may be folded over upon said second front portion releasably held in place by said complementary snap fastener element to conceal the fastener element on said second front portion when the garment is in an open position.

4. A garment construction as defined in claim 3 where-
in a row of tab extensions and complementary fastener ele-
ments are secured along the opposite edges of the garment
opening.

5. In a garment or the like having an opening, comp-
lementary male and female snap fastener elements at-
tached to the garment on opposite sides of the opening,
said elements having fastening portions facing inwardly
along one side whereby they are normally concealed and

10
15

4
facing outwardly on the opposite side whereby they are
normally exposed when the fasteners are disengaged; the
improvement which consists of flexible supporting means
attached to the garment along the edge of said opening
at that side of the garment where the fastener elements
are normally exposed when the fasteners are disengaged,
said supporting means having fastener elements comple-
mentary to those on the side to which said flexible sup-
porting means is attached so that said supporting means
may be folded back and snapped over said normally ex-
posed fastener elements in order to conceal them when
the garment is open.
